DEVICES MANUFACTURING COMPANY, OF CHICAGO, ILLINOIS, A CORPORATION
OF ILLINOIS.

AUTOMATIC VALVE MECHANISM.

1,082,744.

Specification of Letters Patent. Patented Dec. 30, 1913.

Application filed January 7, 1908. Serial No. 409,697.

To all whom it may concern:

Be it known that I, JOHN S. GOLDBERG, citizen of the United States, residing at Chicago, in the county of Cook and State of Illinois, have invented a certain new and useful Improvement in Automatic Valve Mechanism, of which the following is a full, clear, concise, and exact description, reference being had to the accompanying drawings, forming a part of this specification.

My invention relates to automatic valve mechanism, particularly to automatic fuel level controlling means for carbureters.

The main object of my invention is to provide for such construction that the operative parts of the automatic valve mechanism are always visible, the chamber in which the parts are disposed being in greater part of glass or other transparent material.

In the accompanying drawings which clearly illustrate my invention Figure 1 is a side elevation of a carbureter showing my improved valve mechanism applied thereto; Fig. 2 is a top view of the carbureter; Fig. 3 is a sectional view taken on line 3—3, Fig. 2; Fig. 4 is a top view of the valve mechanism, the cover and float being removed.

1 represents the body frame of the carbureter, comprising the inner and outer walls 2 and 3 which form a heating chamber or jacket between them and the inner wall forming a mixing chamber or passageway 4 into which extends a nozzle 5 suitably supported from the framework 1. A circular shelf 6 extends laterally from the body frame and forms the lower wall of a float chamber or reservoir 7. From the lower side of this shelf extends the threaded flange 7' to which is secured the coupling tip 8 by means of a threaded flange nut 9, the tip having inlets 9' for connection with a source of fuel supply. The inner end 10 of the tip is tapered to fit the tapered inner face of the flange, so that when the nut 9 is drawn up its flange 11, engaging the tip, will clamp the tip into the flange to form an oil-tight fit. In the tip a strainer 12 is suitably arranged for straining the oil flowing to the float chamber. Extending upwardly from the center of the circular shelf is the tubular standard 13 through which passes the valve shaft 14 carrying at its lower end the valve spindle 15 whose tapered end 16 is adapted

for engaging the tapered seat 17 surrounding the passageway or port 18 through the shelf at the lower end of the tubular part 13. The walls of the tube part 13 near the base thereof have slots 19, two such slots being shown opposite each other. In each slot 60 there is pivoted a lever frame 20, the pivot point 21 for each lever passing through the walls or extensions 22 at the sides of the corresponding slot. The inner end 23 of each lever engages the shoulder 24 between 65 the valve shaft and the spindle. The outer end 25 of each lever engages against the under side of a float member 26, while a stop extension 27 on each lever is adapted to engage the shelf 6 to limit the downward movement of the float member. This float member is constructed of sheet material to form an annular float chamber 28 having the central sleeve 29 which slides over the tubular standard 13. The cylindrical wall of the 75 float chamber is formed by a section of glass tubing 30 which is held in place on the shelf by the retaining flange 31, a washer 32 being inserted between the glass tube and shelf. The top inclosing wall of the float chamber 80 is provided by the cap or cover 33 having the downwardly extending flange 34 for receiving the upper end of the glass tube, a washer 35 being inserted. The upper end of the tubular standard 13 is threaded for receiving the threaded hub 36 of the cap, the outer surface of the flange 34 being knurled so that the cap can be easily and powerfully turned to clamp the glass tube between the cap and the shelf, thus forming an oil-tight 85 float chamber. The upper section 37 of the valve shaft 14 is of reduced diameter to provide a shoulder 38, and a spring 39 within the tubular standard and encircling the shaft section 37 rests at its lower end 90 against this shoulder. The upper end of the threaded part of the tube is engaged by the cap nut 40 which forms the upper abutment for the spring 39. Above the shaft part 37 is the end section 41 of still less diameter 100 which passes through the opening 42 through the cap nut and which terminates in a head 43. Interposed between the cap nut 40 and the hub 36 is a collar 44 from which a pivot arm 45 extends upwardly and at whose upper end at 46 is pivoted a bell crank lever 47. One arm 48 of this bell crank lever extends under the head 43 of

the valve shaft, while the other arm 49 is adapted for connection with levers or rods to be controlled from a distance. In a pocket 50 formed in the upper end of arm 45 is a compression spring 51 acting against the lug 52 extending downwardly from the bell crank lever, this spring serving to hold the arm 48 of the lever down against the cap nut 40 and away from the head 43, so that the valve shaft can be manually operated vertically. The collar 44 is clamped in place between the cap nut and the cover 33 and cap nut and cover mutually lock each other in place on the tubular standard 13, the outer surface of the cap nut being also knurled so that it can be powerfully tightened by hand.

If the float chamber is empty the weight of the float member 26 is sufficient to rotate the levers 20 to cause the valve shaft 8 to be raised against the pressure of spring 39, so that the valve point 16 is disengaged from the seat 17 to thereby open port 18, so that gasoline may enter from the supply source through an inlet 9', through port 18, into the interior of tube standard 13 and into the float chamber 7 through the slots 19. As the oil in the float chamber rises its floatation effect on the float member gradually releases the weight of the float member from the levers, and the valve rod gradually moves downward until the valve end finally engages the seat to close port 18 when the oil has reached a predetermined level in the float chamber, indicated by dotted line 7, and the flow of oil to the reservoir is cut off. When there is no oil in the reservoir the weight of the float member overcomes the pressure of the spring 39 and depresses the levers 20 to open port 18, but as soon as the oil reaches a predetermined level in the chamber and the effect of the float member is removed from the valve rod, the spring will serve to maintain the valve on its seat.

Carbureters are usually subjected to vibration, jarring or jolting, particularly when applied to vehicle engines, and unless the spring 39 is provided the valve rod would vibrate and jump and would open the port 18, thus causing undue rise of the level and flooding of the carbureter through the nozzle 5 which is connected with the reservoir through passageway 53. The spring 39 is therefore made just stiff enough to overcome the tendency of the valve to vibrate or jump from its seat but to allow the float member to maintain its automatic control over the valve during the varying level of oil in the float chamber under normal conditions.

The passageway 4 of the carbureter communicates with the chamber 54 controlled by disk valve 55 and adapted by means of flange 56 for connection with the engine to be supplied, and the suction of the engine

draws air into the lower end of the passageway 4 which flows past the nozzle and draws gasoline therefrom, which becomes gasified and thoroughly mixed with the air before reaching the engine. As soon as the level in the reservoir drops the float, of course, automatically adjusts the valve mechanism to allow refilling of the chamber. Sometimes sufficient gasoline cannot be obtained from the nozzle for starting the engine and the priming cup 57 is adjustably secured on the threaded stem 58 extending from the carbureter frame and held in place by the clamping nut 59. If more gasoline is desired for starting the engine the valve shaft can be manually raised by raising the head 43, thereby allowing the level in the chamber to rise until oil flows over the nozzle down to the passageway 4 and into the priming cup; then when the engine is cranked the air sucked into the passageway 4 carries with it the oil from the cup and a very rich priming mixture is formed for starting the engine, and thereafter the engine is supplied in the normal manner from the nozzle alone. This priming is usually done by the operator from his seat, usually at a distance from the carbureter, and suitable lever mechanism is provided connected with arm 49 of bell crank lever 47 so that this bell crank lever may be rotated and its arm 48 caused to engage the head 43 to raise the valve rod. The crank arm or lever 60 connected to the shaft 61 on which the throttle valve 55 is mounted, is also connected with lever mechanism controlled by the operator so that he can control the throttle valve and thereby the supply of gas to the engine.

The valve controlling the level of oil in the float chamber may be considered as the most important valve of the carbureter, as if the level is not properly maintained the carbureter cannot operate perfectly and efficiently, and it is therefore very important that the operation of this valve can be readily followed and seen, and the feature of having practically the entire float chamber of transparent material so that the float member and valve are at all times fully visible and so that their operation can be closely followed, is very important.

Not only are the main parts of the automatic valve fully visible, but the entire valve mechanism can be very readily disassembled and reassembled without the use of tools. The cap 33 having the knurled flange and having threaded engagement with the tubular standard at the center can be turned manually with great leverage and force to securely clamp the glass tube between the cap and supporting shelf and the cap nut 40, being also knurled, can be turned down powerfully against the collar 44 to securely bind itself to the threads and to assist in locking the cover against displacement.

Having described my invention I desire to secure the following claims:

1. In a device for controlling the level of fluid fuel for a carburetor or other point of consumption, the combination of a lower wall, a glass tube on said wall, a hollow rod extending upwardly from the lower wall concentrically through and beyond the glass tube, a cap for closing the upper end of the tube and having threaded engagement at its center with the rod whereby said glass tube may be clamped between the cap and the lower wall to form therewith a supply chamber, a valve stem extending through the hollow rod, a valve at the lower end of said valve stem, there being an inlet opening through the lower wall controlled by said valve, a float member surrounding and adapted for vertical reciprocation on said rod, lever mechanism connecting between said float member and the valve stem and arranged so that downward movement of the float member will cause upward movement of the valve stem, spring mechanism tending to hold the valve to close the inlet opening, said float member being governed by the level of fluid within the chamber and co-operating with the spring to regulate the size of the inlet opening in proportion to the level of fluid within the chamber, said glass tube rendering visible the float member and the valve mechanism whereby their operation may be observed, a cap nut having threaded engagement with the upper end of the hollow rod to close the end of said rod and to guide the upper end of the valve stem, and lever mechanism clamped to the rod between the cap nut and cap for controlling the operation of the valve independently of the float member and spring. 70
2. In a device for controlling the flow of fluid fuel to a point of consumption, the combination of a lower supporting wall, a cylindrical wall carried by said lower wall, a tubular rod extending axially from the lower wall and through the cylindrical wall, a cap engaging the upper end of the cylindrical wall and having threaded engagement with the threaded upper end of the tubular rod, a locking collar engaging the threaded end of the tubular rod and engaging the cap, said walls forming a reservoir for fluid fuel, 80 an inlet in said lower wall, a valve for controlling the flow through said inlet, a valve stem extending upwardly through and from the tubular rod, a float member within the reservoir having connection with said valve stem, and lever mechanism carried by said locking collar and adapted for engagement with the upper end of the valve stem to control said valve. 85
3. In a device for controlling the flow of fluid fuel to a point of consumption, the combination of a lower supporting wall, a cylindrical wall carried by said lower wall, a tubular rod extending axially from the lower wall and through the cylindrical wall, 90 a cap engaging the upper end of the cylindrical wall and having threaded engagement with the threaded upper end of the tubular rod, a locking collar engaging the threaded end of the tubular rod and engaging the cap, said walls forming a reservoir for fluid fuel, 95 an inlet in said lower wall, a valve for controlling the flow through said inlet, a valve stem extending upwardly through and from the tubular rod, a float member within the reservoir having connection with said valve stem, and lever mechanism carried by said locking collar and adapted for engagement with the upper end of the valve stem to control said valve. 100
4. In a device for controlling the flow of fluid fuel to a point of consumption, the combination of a lower supporting wall, a cylindrical wall carried by said lower wall, a tubular rod extending axially from the lower wall and through the cylindrical wall, 105 a cap engaging the end of the cylindrical wall and having threaded engagement with the threaded upper end of the tubular rod, a locking collar engaging the threaded end of the tubular rod and engaging the cap, 110 said walls forming a reservoir for fluid fuel, an inlet in said lower wall, a valve for controlling the flow through said inlet, a valve stem extending upwardly through and from the tubular rod, a float member within the reservoir having connection with said valve stem, an upward extension on said locking collar, a bell crank lever pivoted at its elbow to said extension, and a head at the upper end of the valve stem, one limb of the bell 115 crank lever being adapted for engagement with said head and the other limb of said lever being adapted for connection with actuating mechanism, actuation of said bell crank lever causing adjustment of the valve 120 stem and valve. 125
5. In mechanism for controlling the flow of fluid fuel to a point of consumption, the combination of a lower supporting wall, a cylindrical wall supported on said lower 130

wall, a tubular rod extending upwardly from the lower wall and through the cylindrical wall, said rod having its upper end threaded, a cap engaging the upper end of the cylindrical wall and having threaded engagement at its center with said rod, said walls forming a reservoir for fluid fuel, an inlet in the lower wall, a valve controlling said inlet, a valve stem extending upwardly through and beyond said rod, a float member guided on said rod, lever mechanism connecting said float member with the valve stem, a locking collar having threaded engagement with the rod for locking the cap in position, a cap nut engaging and closing the upper end of the valve stem, said valve stem extending through the upper wall of said cap nut and being guided thereby, a head at the upper end of said valve stem, an upward extension from said locking collar, and a lever pivoted to said upward extension, one end of said lever being adapted for association with the valve stem head and the other end of said lever being adapted for connection with actuating mechanism, actuation of said lever enabling adjustment of said valve independent of the float member.

6. In a device for controlling the flow of liquid fuel, the combination of a lower supporting wall, a vertical inclosing wall mounted on said lower wall; a tube extending upwardly from the lower supporting wall within the inclosing wall, a cap adapted to rest on said inclosing vertical wall, said cap having threaded engagement with the

upper end of said tube, thereby clamping said inclosing wall between the cap and the supporting wall and forming a reservoir for liquid fuel, an inlet in the lower wall, a valve for controlling said inlet, a valve stem extending upwardly through said tube, a spring in said tube tending to move said valve stem downwardly, a float member within said reservoir, lever mechanism connecting said float member with the valve stem, thereby controlling the size of the inlet opening, and means on the top of said cap for directly controlling said valve stem.

7. In a carbureter, a float chamber having an inlet in the bottom and an outlet, said inlet being surrounded by a valve seat, a needle valve member guided in and extending through the top of said chamber, the end of said member coöperating with said seat, a float, means for transmitting the movement of said float to said valve member, an angularly adjustable collar on said top, a lever pivoted on said collar and adapted to have one of its arms engaging part of said needle valve member, and a spring for normally holding said lever out of such engagement with said needle valve member.

In witness whereof, I hereunto subscribe my name this 4th day of January A. D., 1908.

JOHN S. GOLDBERG.
